Specification of Letters Patent.

Patented Oct. 18, 1921.

Application filed July 19, 1918. Serial No. 245,730.

To all whom it may concern:

Be it known that I, STEPHEN A. DOBYNE, a citizen of the United States, and residing at St. Louis, Missouri, have invented the 5 new and useful Improvement in Fasteners and Slug-Inserting Machines, of which the following is a specification.

This invention relates to machines for inserting fasteners and slugs, and more particularly to machines adapted for operation on boots and shoes.

Metallic machines as used on boots and shoes, are used for two distinct operations, namely, sole attaching and slugging operations. In the sole attaching operation, the fastener is driven through the sole and clenched on the insole, while in the slugging operation, a series of wear resisting slugs are driven along the edge of the sole or heel to 20 form a wear resisting surface. In the sole attaching operation, a headed fastener, that is, a fastener having a laterally projecting head, must be used in order to provide an anchorage in the outsole; the anchorage in 25 the insole is, however, provided by the clench of the fastener point on the anvil. In the slugging operation it is unnecessary to provide the slug with a head, since it performs only the function of a wear resisting member, and not of a fastening member. For 30 economical reasons, therefore, the head is omitted.

In the sole attaching operation, the spacing of the fasteners is considerable, while 35 in the slugging operation, the slugs are driven close together, sometimes as close as one-eighth of an inch. Now where a metallic machine is adapted for both of these operations, as is for instance the case in repair 40 shops, where duplication of machines is, for economical reasons, not desired, it is necessary to vary the feed considerably; sometimes this feed varies from three-thirty-seconds of an inch for slugging, to fifteen- 45 thirty-seconds of an inch for sole attaching. Now since an awl feed machine necessarily requires a construction in which the awl and the throat are movable into and out of the line of drive, a certain clearance movement 50 must necessarily be given to the awl, on account of the thickness of the throat wall be-

tween the driver passage and the awl. With the ordinary constructions providing for a variation in feed, the clearance must, of course, necessarily increase with the feed 55 movement, so that with a maximum feed, the total movement given to the awl is necessarily great, resulting in great vibration and wearing of the awl cam. For these reasons, therefore, the successful operation of a machine for interchangeably inserting fasteners or slugs, requires the design of special mechanism for imparting a work feeding movement to the awl, but in such a manner as to reduce the total movement to a least 60 possible minimum. Metallic machines are of various types, of which the principal ones are loose nailing machines, wire nailing machines, and string nailing machines. A loose nailing machine is not commercially adapt- 65 able for both sole attaching and slugging operations. A wire nailing machine, while adapted for slugging, is not adapted for sole attaching, for the reason that in sole attaching, it is absolutely essential to provide a headed fastener in order to obtain an 70 anchorage of the fastener in the outsole.

A string nailing machine is, on the other hand, peculiarly adapted, when properly constructed, and when the string nail is 80 properly designed, for either sole attaching or slugging. For sole attaching, however, the string of connected fasteners should be so constructed that each fastener will have a laterally extending head to provide the 85 necessary anchorage in the outsole. For slugging, however, this head is not only unnecessary, but even undesirable, and should, therefore, be omitted. The result is, therefore, that in a machine for selectively 90 inserting fasteners or slugs, and utilizing strings of connected fasteners and of connected slugs, the total width of a fastener string is greater than that of the slug string. As a matter of fact, the slug string width 95 is about that of the shank of a fastener on the fastener string.

On account of the peculiarities in the material operated upon, a machine for selectively forming from strings of connected 100 fasteners or slugs, detached fasteners or slugs, and for selectively driving such de-

tached fasteners or slugs, special provisions must be made, and special problems in design and construction are encountered. Thus, the mechanism for guiding the strings 5 of connected fasteners and connected slugs must be so designed and so coördinated with the mechanism for selectively feeding these strings, and for selectively cutting or detaching fasteners or slugs from a selected 10 string, that the mechanism can be readily controlled or adjusted to feed a selected fastener string or slug string, and to cut from the selected string, a fastener or a slug. Moreover, the throat or receiving member 15 which receives and positions in the line of drive, a detached slug or fastener, must be so constructed and coördinated with the mechanism for feeding and cutting, that the machine can be readily controlled to position 20 in the throat at will, a fastener or a slug. Moreover, the throat itself must be constructed to retain and properly direct or guide during the driving operation, either a fastener or a slug. This requires development in design and construction, in order 25 that a throat may interchangeably receive and control during the driving operation, such radically different metallic elements, as a headed fastener and a headless slug.

30 It will thus be seen that the design and construction of a machine utilizing strings of connected fasteners and strings of connected slugs, and which will, at the will of the operator, drive either of these metallic 35 elements, involves the solution of special problems, and the construction and coördination of special mechanism.

One of the objects of this invention, therefore, is to provide and produce a machine, 40 utilizing strings of connected fasteners and connected slugs, which is so constructed and arranged as to selectively permit the formation from a selected fastener string or slug string, of a fastener or slug, and the driving of such a formed fastener or slug into the work.

Another object is to provide a machine of this type with an awl feed mechanism, which is constructed and arranged for control, to adapt the machine for either fastening or slugging operations.

Further objects will appear from the detailed description taken in connection with the accompanying drawings, in which,

55 Figure 1 is a front elevation of a machine embodying this invention;

Fig. 18 is a cam diagram showing the 80 sequence of operation of the parts.

Referring to the accompanying drawings, and first more particularly to Figs. 1, 2 and 3, the machine there shown is generally of the construction shown in Patent No. 85 1,286,559, December 3, 1918. It comprises generally, a column 1 upon which is mounted a machine head 2 provided with bearings for sustaining the various movable parts, among which is a main drive shaft 3, which 90 is provided with a suitable clutch and brake (not shown). Fixed to this shaft are cam wheels 4, 5 and 6, each of which is provided on both of its side faces with grooved cams. A suitable horn 7 supports the work against a presser foot 8, and there is also provided, if desired, a welt guide 9, fixed to the machine head. Pivoted at 10 on the machine head, is a throat 11, having a driver passage with which coöperates a driver 12, attached to a 100 driver bar 13, mounted in a suitable guide 14 on the machine head, and operated by a cam in the right face (Fig. 2) of the cam wheel 4. Pivoted also at 10 is a nail guide 15, grooved to receive a series of strands of connected nails. Pivoted at 17 on the machine head is an arm 18 having pivoted thereto, an arm 19, normally moved in a counter-clockwise direction by a spring plunger 20, and having a feeding and cutting member 21, 110 adapted to feed the string of nails into the throat and coöperate with the throat to cut a nail from the string. The arm 18 and the cutter are operated from a cam groove in the left side (Fig. 2) of the cam wheel 6. 115 The string nail guide 15 is held by a spring 22 against a stop 23 on the machine head, while the throat has connected therewith, an arm 24, operated by a cam groove in the right face (Fig. 2) of the cam wheel 5. 120 Mounted in a guide 25 on the machine head is a slide 26, carrying an awl bar 27, provided at its lower end with an awl 28. This awl bar is reciprocated vertically by means of an arm 29, on a rock-shaft 30, which has an arm 31, provided with a cam roll engaging a cam 125 groove in the right face (Fig. 2) of the cam wheel 6. The mechanism so far described,

except as hereinafter noted, is of substantially the construction as shown in my patent referred to.

5 *The awl feed mechanism.*

As pointed out above, in an awl feed machine it is necessary that the throat and awl be movable into and out of the line of drive, so as to position the awl hole in the line of 10 drive to receive the fastener or slug. The distance between the center of the awl and the center of the driver passage in the throat cannot, however, for constructional reasons, be less than a given amount; as a matter of 15 fact, in a substantially constructed shoe machine, this distance cannot be less than nine-thirty-seconds of an inch. This can readily be seen on reference to Figs. 14 and 15. Now if it is desired to space the fasteners, such 20 as slugs, less than the distance between the awl and the driver passage, then it is necessary to move the awl laterally while it clears the work, a distance equal to the difference between the spacing of the awl and the driver 25 passage and the desired feed of the work. In other words, the awl must be moved laterally from a position shown in Fig. 14, to a position shown in Fig. 15, before this awl can be moved downwardly to pierce the work. 30 This means that the awl must be moved in such a case, in successive steps, one of which is a clearing step, and the other is a work feeding step, the awl being moved downwardly to pierce the work during the dwell 35 between the steps.

Where a single cam is used to move the awl laterally through both successive steps with a dwell therebetween, then the clearing and feeding movements have fixed definite 40 relations, so that one will necessarily increase with the other. Thus, where as in Fig. 16, (top diagram) the machine is set, for instance, for its minimum feed of five-thirty-seconds of an inch, the clearing 45 movement must necessarily be four-thirty-seconds of an inch. If now the machine is set for, for instance, the maximum feed, Fig. 16, (lower diagram) of say, fifteen-thirty-seconds of an inch, then the clearing 50 movement will necessarily be twelve-thirty-seconds of an inch. In other words the total travel of the awl for a maximum feed will be twenty-seven-thirty-seconds of an inch, that is, nearly twice the effective feed 55 movement of the awl. In view of the fact, however, that these machines are made to run at high speeds, such an excessive travel of the awl and its supporting slide, causes undue vibration of the machine, very soon wears 60 out the cam, and in fact, tears the machine to pieces.

In accordance with this invention, the awl is moved laterally in successive steps with an intervening dwell. The first step is a

work clearing step and the awl is at that time clear of the work; the second step is a work feeding step and the awl is at that time in the work. Separate actuating cams are provided for imparting to the awl these 65 separate successive movements. Adjusting 70 or controlling mechanism is provided for adjusting or controlling the feed movement of the awl, and this also adjusts or controls the clearing movement; the clearing movement, however, decreases as the feeding movement 75 increases, from a maximum clearing movement, corresponding to a minimum feeding movement, to zero clearing movement, corresponding to maximum feed movement of the awl. 80

Referring now to Figs. 1 to 6 inclusive, 85 designates a lever pivoted at 36, and having its lower end engaging a stud 37 on the feed slide 26, and provided at its upper end with a cam roll 38, engaging a cam groove 39 in the cam wheel 4. The pivot 36 of the lever 35, is in the form of a stud, which has a block 40 sliding in a guide-way 41 on the lever 35. This stud is fixed to a shank 42, sliding in a guide-way 43 in a 90 crank 44, fixed to one end of a rock-shaft, the other end of which has fixed thereto an arm 46, provided with a cam roll 47, moving in a cam groove 48 in the cam wheel 5. The shank 42 is provided with teeth 49 meshing 95 with a toothed shaft 50, mounted in the bushing 51 in the crank 44, and provided with an arm 52. Mounted between a nut 53 and the crank 44, is a plate 54 provided with an arm 55, and with a cam surface 56, engaging a locking pin 57, which slides freely in a bearing in the crank, and bears against a flattened portion 58 on the shank 42. The cam rolls 38 and 47 are mounted on studs which are eccentrically mounted in the ends 100 of the arms 35 and 46 respectively, the ends of these arms being split and adapted to be clamped on the eccentric studs. This enables the cam rolls to be adjusted with respect to the cam grooves, and locked in adjusted position. 105

The cam groove 48 is adapted to impart to the feed slide and the awl thereon, the work clearing movement, while the cam groove 39 imparts the work feeding movement, the awl piercing cam operating the arm 31 and the awl connected therewith, to cause the awl to pierce the work during the dwell between the clearing and feeding movements of the awl. This is clear from the cam diagram, Fig. 18. When the stud 36 is opposite the center of the rock-shaft 45, the feeding movement by the cam groove 39 is a maximum. It will be noted, however, that at this time, the clearing movement will be 115 zero, as the movement of the arm 46 by the cam groove 48, will, at this time, have no effect whatsoever upon the feed slide. As, 120 125

however, the stud 36 moves down with its shank 42, and away from the center of the rock-shaft 45, the feeding movement of the feed slide by the cam groove 39, will be decreased, but the clearing movement of the feed slide by the cam groove 48, will be increased. In the lowest position of the stud 36, the feed movement will be a minimum, while the clearing movement will be a maximum. It will, of course, be understood that the shank 42 is adjusted after releasing the pin 36, as shown in Fig. 6, by turning the handle 52, and after the shank 42 has been set in adjusted position, this shank is locked 15 by moving the handle 55 toward the observer.

Fig. 17 shows the actual operation. The cam grooves 39 and 48, and the arms 35, 46 and 44, are so proportioned, that with a minimum feed, the clearing movement of the awl will be sufficient, so that the feed movement plus the clearing movement will equal, or be slightly greater than, the distance between the center of the throat and the center of the awl. Thereafter, with an increase of feed, as pointed out heretofore, the clearing movement will decrease uniformly, so that with a maximum feed movement, as shown in the lower diagram Fig. 17, the total movement of the awl will be a feeding movement, in that the clearing movement is at this time reduced to zero, on account of the fact that the stud 36 is at this time opposite the center of the shaft 45.

It will, therefore, be seen that with this construction, the maximum movement of the feed slide can never be greater than the maximum feed movement of the awl, so that this maximum movement is nearly cut in half, as compared to a construction in which a single cam groove or actuator is used, as illustrated in Fig. 17. With this construction, therefore, the vibration of the feed slide is reduced to a minimum.

The presser foot.

The presser foot is fully described in my application Serial Number 174,096, filed 50 June 11, 1917. As shown and described in said application, the presser foot is mounted on a carrier 60, pivoted at 61 to the machine head, so as to adapt the presser foot for vertical adjustment, so as to vary the position of its lower face with respect to the lower limit of movement of the bottom of the driver. This presser foot is adjusted by an actuator 64. The extent of the insertion of the fasteners can, therefore, be readily 60 varied by adjusting the presser foot, so as to cause the fasteners to be inserted countersunk, flush, or slightly protruding from the upper face of the work. The machine is, therefore, adaptable to different classes of 65 work, without requiring readjustment of the

driver. The bottom of the presser foot has mounted thereon, a work guide 69, which is adjusted by a head 72, as described in the application referred to.

The feeding and cutting mechanism.

The feeding and cutting mechanism is fully described in my application Serial Number 174,096, filed June 11, 1917, referred to. Referring to Figs. 1 and 3, shaft 17 has fixed thereto, an arm 75, which is yieldingly connected through a spring 85, with an arm 79, having a cam roll engaging a cam in the right side (Fig. 3) of the cam wheel 6. It will, therefore, be seen that 80 there is a yielding connection between the cam and the arm 18. The spring 85 is, of course, strong enough so as to cause the cutter to move the nail guide 15, and against the die plate 76, (Fig. 7) on the throat to cut 85 off a nail. If, however, the driver should break and project from the throat, so as to prevent movement of the nail guide to the right, Fig. 1, to feed the string and cut off the nail, then the spring 85 will yield and 90 thus prevent breaking or shifting of the feeding and cutting blade 21 in its arm 19.

The nail guiding mechanism.

Referring now to Figs. 7 to 11 inclusive, 95 the nail guide 15 is mounted on a plate 88 which, as heretofore referred to, is pivoted at 10. This plate has a laterally projecting arm 89, provided with a laterally projecting pin 90, to one end to which is attached the 100 spring 22. The arm 89 has a laterally projecting lug 91, bearing against the stop 23 which, as shown, is eccentrically mounted in the machine head, so as to permit adjustment thereof, to align the nail guide 15, 105 with a driver passage 77 in the throat.

The nail guide is provided with a series of grooves adapted to receive the stock. In the specific embodiment shown, the nail guide is provided with a series (in this case three) of deep grooves 78, adapted each to receive a string of connected fasteners F, and with a shallow groove 80, adapted to receive a string of connected slugs S. The string of 115 connected fasteners F, as shown in Figs. 7 and 10, is constructed so as to provide a series of headed fasteners connected end to end; the string of connected slugs S, however, is constructed to provide a series of headless slugs connected end to end. The shank width of a slug is substantially the same as the shank width of a fastener. Accordingly, in order to enable the feeding member 21 to properly engage the head end 120 of a slug on the string S, it is necessary that the groove 80 be shallow, and that the nail guide be undercut, as shown at 81, to permit projection of the slug edge beyond the groove 80, as shown in Fig. 11.

Pivoted at 92 on the plate 88 is an arm 93, 130

which is connected by a link 94 with an arm 95, pivoted at 90 on the arm 89, and having a handle 96. Attached to a laterally projecting lug 97 on the arm 93, is a plate 98, which 5 is stepped to provide a series of guards 99, overlying the fastener string groove 78, and providing a guard 100, overlapping the slug string groove 80. These guards provide stop pawls adapted to engage the head ends of the 10 fasteners or slugs on the strings, and adapted to be engaged by the feeding and cutting member 21, so as to permit the feed of only one fastener or slug at a time. It will, of course, be seen that the stepping of the plate 15 98, to provide the guards 99, permits the fastener string grooves 78 to receive strings of fasteners of different lengths. Overlying the plate 98 is a spring plate 101, which keeps the guards under tension. This plate 20 is apertured, as shown at 102, so as to permit insertion of the strings of nails therein. Attached also to the plate 97 is a spring plate 103, which has a rounded extremity 104 bearing against the nail guide for the 25 purpose of holding the strings in the guide grooves 78 and 80.

When the parts are in full line position, as shown in Fig. 7, with the crank 95 over center, the guards will be held in engagement 30 with the guide 15, and since these guards are at this time under tension, the parts will be held in locked position. When, however, the handle 96 is moved to dotted line position, the guards are swung out of engagement 35 with the guide, thereby permitting ready removal of the string or strings from the guide.

The nail guide shifting mechanism.

40 Referring now to Figs. 1, 2, 3, 12 and 13, the shaft 10 of the nail guide is mounted for rotating and sliding movement in a bearing 110, in the machine head 2. Fixed to this shaft 10 is a grooved collar 111, which is 45 held in its normal position with the slug guide groove 80, in alinement with the driver passage, and the feeding and cutting blade 21, by a spring 112, encircling the shaft 10, and bearing at one end against the collar 50 111, and at its other end against the bearing 110. This collar is engaged by the forked arm 113 of a lever pivoted at 114 on a bracket 115, mounted on the machine head. The other arm 116 of this lever, has pivoted 55 thereon at 117, a handle 118, so that by manipulation of the handle 118, the lever may be swung on its pivot 114, to shift the shaft 10 endwise, in order to shift the string nail guide 15, so as to aline any selected fastener 60 or slug groove 78, 80, with, and in coöperative relation with respect to, the feeding and cutting blade 21 and the throat 77. In order to lock the actuating lever 116 and, therefore, the string nail guide, in any position 65 of adjustment, the handle 118 is provided

with an extension 119, bearing a spring pressed plunger 120, adapted to engage with and enter a series of depressions 122, in a sector 123 on the bracket 115. To firmly hold the plunger 120 in its depression, a 70 spring 124 is provided, which engages at one end with an extension 125, on the arm 118, and at its other end with an extension 126, on the lever arm 116. With this construction the operator can at pleasure, by manipulation of the handle 118, shift the string nail guide to aline any one of the guide grooves in alinement with the feeding and cutting blade and the throat, and the parts will be locked in any position of adjustment. 75 80

The throat or receiver.

Referring now to Fig. 7, the throat 11, as shown, is provided with a recess 130, in 85 which projects a fastener or slug guiding or directing member 131, provided with a fin 132 projecting into the driver passage. This member 132 is pivoted at 133 in the recess 130, and is moved into the driver passage by 90 a plunger 134, engaged by a spring 135, in a tube 136, screwed into the throat. The fin 132 has a projection 137, adapted to engage the throat wall for the purpose as herein-after described. 95

The fin 132 is so formed and spaced from the opposite throat wall, so as to enable it to receive the headed fastener which is fed into and cut off in the driver passage. In order, however, that a slug may be properly retained and driven in and through the same driver passage, it is necessary to provide means which will accommodate itself to a headed fastener with a laterally projecting head, and to a slug having a shank about the 105 size of a fastener shank. It is for this purpose that the projection 137 is provided on the fin. This projection retains the slug in the driver passage, as shown in Fig. 7, and being beveled, it yields when the fastener is 110 being driven by the driver, and engages with the edge of the slug or the shank of the fastener as the slug or fastener is driven into the work, so as to hold either the slug or the fastener firmly against the opposite driver 115 passage wall, in order that the slug or fastener will be directed and guided while it is being driven. It will, therefore, be seen that the throat is adaptable to either a headed fastener or a slug. 120

Résumé of operations.

In the general operation of this machine, and starting with the awl up, the awl will be moved laterally, executing a clearing movement, and this awl will thereafter descend into the work to form a puncture therein. At this period the horn is depressed to un-clamp the work, and the awl will now be given a feeding movement to feed the punc- 125 130

ture into the line of drive. During the lateral movement of the awl, the throat will have swung out of the line of drive. (That is the line on which the fastener is driven and which passes vertically through the horn, and the driver and throat when above the horn tip). The puncture having been placed in the line of drive with the feeding movement of the work completed, the awl is retracted and begins to return, followed by the throat, which is now moved into the line of drive. While the throat is out of the line of drive, so that the driver passage will be in alignment with the string nail guide, the feeding mechanism will operate to feed a string of connected nails or slugs into the throat, and cut off the lowermost nail from the string to position a cut fastener or slug in the throat. As the throat moves back into the line of drive, the driver descends to drive the fastener or slug positioned in the driver passage, into the puncture formed in the work and positioned at this time in the line of drive.

In order to adjust the machine for either fastening or slugging operations, it is necessary not only to shift the string nail guide, but also to shift the work feeding mechanism. Those two mechanisms, therefore, constitute the dominating mechanisms, which selectively adapt the machine to either fastening or slugging operations. In order, for instance, to adapt the machine for fastening operation, the string nail guide is shifted, adjusted or controlled to shift any selected fastener guiding groove and the fastener or slug stock therein into the plane of drive (that is into a vertical plane passing through the driver, horn, awl and the feeding and cutting mechanism) and into co-operative relation with respect to the feeding and cutting mechanism, and with respect to the throat; the work feeding mechanism is, however, also shifted, adjusted or controlled, so as to adapt the operation of the awl to the position to which the nail guide is shifted. Thus, for instance, the nail guide is shifted to permit the forming and driving of a certain size of fastener, and the work feeding mechanism is adjusted or controlled to bring the work feeding mechanism in accord with the selected fastener. This means, of course, that for fastening operation, the feed of the work must be increased to a maximum, and this can be accomplished with the awl feed mechanism embodying this invention, with a minimum movement of the actuating mechanism, on account of the fact that the clearance movement decreases to a minimum with the increase of the awl feeding movement required for fastening operation.

When it is desired to convert the machine into a slugging machine, the operator will shift the string nail guide to position the slug string groove in proper co-operative re-

lation with the feeding and cutting mechanism and the throat, in order to position the slug string in the line of drive; the work feeding mechanism is also, at this time, adjusted to a minimum, so as to adjust the feeding movement of the awl in accordance with the position of the string nail guide, in order to adapt the machine for slugging operation. The clearing movement of the awl is, of course, at this time, a maximum, but since the feeding movement is a minimum, the total movement of the awl is not excessive, and is, in fact, a minimum.

It will, therefore, be seen that the invention accomplishes its objects. An awl feed string nailing machine is produced which utilizes strings of connected fasteners and connected slugs, in which the parts are so constructed, arranged and coöordinated, as to selectively permit the formation from a selected fastener string or slug string, of a fastener or slug, and permit the driving of such a formed fastener or slug into the work. The nail guide has a special construction adapting it for guiding strings of connected fasteners, and a string of connected slugs, and this nail guide is so constructed and so coöordinated with the feeding mechanism and the throat, as to permit a selected fastener string or a selected slug string to be shifted at will in the line of drive, to permit the feeding of either a selected fastener string, or a selected slug string into the throat. The throat itself is constructed and arranged to receive and guide, during the driving operation, either a fastener or a slug. The awl feed mechanism is constructed to permit its instant adjustment from a maximum feed required for fastening operation, to a minimum feed required for slugging operation, at the same time maintaining the lowest possible movement of the awl actuating mechanism.

It is obvious that various changes may be made in the details without departing from the spirit of this invention. It is, therefore, to be understood that this invention is not to be limited to the specific construction shown and described.

Having thus described the invention, what is claimed is:

1. In a machine for selectively inserting fasteners or slugs, the combination with driving means, of means for guiding strings of connected fasteners and connected slugs, a throat adapted to selectively receive the strings from said guiding means, feeding and cutting means, constructed and arranged to selectively feed the strings by engagement with the head end of a fastener or slug on a selected string, and constructed and arranged to cut the selected string, adapted to selectively position a cut fastener or slug in said throat, work puncturing and feeding mechanism including a work feeding awl,

and means for moving said awl and said throat into and out of the line of drive.

2. In a machine for selectively inserting fasteners or slugs, the combination with 5 driving means, of means for guiding strings of connected fasteners and connected slugs, a throat adapted to selectively receive the strings from said guiding means, feeding and cutting means, constructed and arranged 10 to selectively feed the strings by engagement with the head end of a fastener or slug on a selected string, and constructed and arranged to cut the selected string, adapted to selectively position a cut fastener or slug in 15 said throat, work puncturing and feeding mechanism including a work feeding awl, means for moving said awl and said throat into and out of the line of drive, and means for adjusting said work puncturing and 20 feeding mechanism, constructed and arranged to selectively adapt the machine for fastening and for slugging operations.

3. In a machine for selectively inserting fasteners or slugs, the combination with 25 driving means, of means for guiding strings of connected fasteners and connected slugs, a movable receiver adapted to selectively receive the strings from said guiding means, feeding and cutting means, constructed and arranged to selectively feed the strings by 30 engagement with the head end of a fastener or slug on a selected string, and constructed and arranged to cut the selected string, adapted to selectively position a cut fastener or 35 slug in said receiver, means for moving said receiver to position the fastener or slug therein in the line of drive, and work puncturing and feeding mechanism including an awl coöoperating with said other elements to 40 feed the work and place the puncture formed therein in the line of drive.

4. In a machine for selectively inserting fasteners or slugs, the combination with 45 driving means, of means for guiding strings of connected fasteners and connected slugs, a movable receiver adapted to selectively receive the strings from said guiding means, feeding and cutting means, constructed and arranged to selectively feed the strings by 50 engagement with the head end of a fastener or slug on a selected string, and constructed and arranged to cut the selected string, adapted to selectively position a cut fastener or 55 slug in said receiver, means for moving said receiver to position the fastener or slug therein in the line of drive, and work puncturing and feeding mechanism including an awl coöoperating with said other elements to 60 feed the work and place the puncture formed therein in the line of drive, and means for adjusting said work puncturing and feeding mechanism, constructed and arranged to selectively adapt the machine for fastening and for slugging operations.

5. In a machine for selectively inserting

fasteners or slugs, the combination with a horn or work support positioned in the line of drive, of a work feeding awl, a driver, a throat adapted to selectively receive a fastener or a slug, means for selectively guiding strings of connected fasteners or slugs into said throat, means constructed and arranged to feed a selected fastener or slug string into said throat by engagement with the head end of a fastener or slug on the 70 selected string, and constructed and arranged to cut the end fastener or slug from the selected string, adapted to position a cut fastener or slug in said throat, and means for moving said throat and said awl 75 into and out of the line of drive.

6. In a machine for selectively inserting fasteners or slugs, the combination with a horn or work support positioned in the line of drive, of a work feeding awl, a driver, a 80 throat adapted to selectively receive a fastener or a slug, means for selectively guiding strings of connected fasteners or slugs into said throat, means constructed and arranged to feed a selected fastener or 85 slug string into said throat by engagement with the head end of a fastener or slug on the selected string, and constructed and arranged to cut the end fastener or slug from the selected string, adapted to position a cut fastener or slug in said throat, means for moving said throat and said awl into and 90 out of the line of drive, and means for adjusting said awl, constructed and arranged to selectively adapt the machine for fastening and for slugging operations.

7. In a machine for selectively inserting fasteners or slugs, the combination with driving means, of fastener controlling mechanism including means for guiding 105 strings of connected fasteners and connected slugs, a throat adapted to selectively receive the strings from said guiding means, feeding and cutting means, constructed and arranged to selectively feed the strings by 110 engagement with the head end of a fastener or slug on a selected string, and constructed and arranged to cut the selected string, adapted to selectively position a cut fastener or slug in said throat, work puncturing and feeding mechanism including a work feeding awl, means for moving said awl and said throat into and out of the line of drive, and means for adjusting said mechanisms, constructed and arranged to 115 selectively adapt the machine for fastening and for slugging operations.

8. In a machine for selectively inserting fasteners or slugs, the combination with driving means, of fastener controlling 125 mechanism including means for guiding strings of connected fasteners and connected slugs, a movable receiver adapted to selectively receive the strings from said guiding means, feeding and cutting means, con- 130

structed and arranged to selectively feed the strings by engagement with the head end of a fastener or slug on a selected string, and constructed and arranged to cut the selected 5 string, adapted to selectively position a cut fastener or slug in said receiver, means for moving said receiver to position the fastener or slug therein in the line of drive, work puncturing and feeding mechanism including an awl coöperating with said other elements to feed the work and to place the puncture formed therein in the line of drive, and means for adjusting the said mechanisms, constructed and arranged to selectively adapt the machine for fastening and for slugging operations.

9. In a machine for selectively inserting fasteners or slugs, the combination with driving means, of means for guiding strings 20 of connected fasteners and connected slugs, a throat adapted to selectively receive the strings from said guiding means, feeding and cutting means, constructed and arranged to selectively feed the strings by engagement with the head end of a fastener or slug on a selected string, and constructed and arranged to cut the selected string, adapted to selectively position a cut fastener or slug in said throat, work puncturing and 25 feeding mechanism including a work feeding awl, means for moving said awl and said throat into and out of the line of drive, and means for adjusting said guiding means and said work puncturing and feeding 30 mechanism, constructed and arranged to selectively adapt the machine for fastening and for slugging operations.

10. In a machine for selectively inserting fasteners or slugs, the combination with 40 driving means, of means for guiding strings of connected fasteners and connected slugs, a movable receiver adapted to selectively receive the strings from said guiding means, feeding and cutting means, constructed and arranged to selectively feed the strings by engagement with the head end of a fastener or slug on a selected string, and constructed and arranged to cut the selected string, adapted to selectively position a cut fastener 45 or slug in said receiver, means for moving said receiver to position the fastener or slug therein in the line of drive, work puncturing and feeding mechanism including an awl coöperating with said other elements to feed 50 the work and to place the puncture formed therein in the line of drive, and means for adjusting said guiding means and said work puncturing and feeding mechanism, constructed and arranged to selectively adapt 55 the machine for fastening and for slugging operations.

11. In a machine for selectively inserting fasteners or slugs, the combination with 60 driving means, of fastener controlling mechanism including means for guiding strings

of connected fasteners and connected slugs, a throat adapted to selectively receive the strings from said guiding means, feeding and cutting means, constructed and arranged to selectively feed the strings by engagement 70 with the head end of a fastener or slug on a selected string, and constructed and arranged to coöperate with said throat to cut the selected string, adapted to selectively position a cut fastener or slug in said throat, work puncturing and feeding mechanism including a work feeding awl, means for moving said awl and said throat into and out of the line of drive, and means for adjusting said mechanisms, constructed and arranged 75 to selectively adapt the machine for fastening and for slugging operations.

12. In a machine for selectively inserting fasteners or slugs, the combination with 80 driving means, of fastener controlling mechanism including a guide for strings of connected fasteners and connected slugs, a throat adapted to selectively receive a fastener string or a slug string from said guide, feeding and cutting means, constructed and arranged to feed a selected string into said throat by engagement with the head end of a fastener or slug on the selected string, and constructed and arranged to coöperate with 85 said throat to cut the selected string, adapted to selectively position a cut fastener or slug in said throat, work puncturing and feeding mechanism including a work feeding awl, means for moving said awl and said throat into and out of the line of drive, and means for adjusting said mechanisms, constructed and arranged to selectively 90 adapt the machine for fastening and for slugging operations.

13. In a machine for selectively inserting fasteners or slugs, the combination with 95 driving means, of fastener controlling mechanism including a guide for strings of connected fasteners and connected slugs, a throat adapted to selectively receive a fastener string or a slug string from said guide, a feeding and cutting member constructed and arranged to engage the head end of a fastener or slug on a selected string to feed 100 said string into said throat and to thereafter cut said string, adapted to selectively position a cut fastener or slug in said throat, work puncturing and feeding mechanism including a work feeding awl, means for moving said awl and said throat into and out of the line of drive, and means for 105 adjusting said mechanisms, constructed and arranged to selectively adapt the machine for fastening and for slugging operations.

14. In a machine for selectively inserting 110 fasteners or slugs, the combination with driving means, of fastener controlling mechanism including a guide for strings of connected fasteners and connected slugs, a throat adapted to selectively receive a fas- 115

- tener string or a slug string from said guide, a feeding and cutting member constructed and arranged to engage the head end of a fastener or slug on a selected string to feed 5 said string into said throat and to thereafter coöperate with said throat to cut said string, adapted to selectively position a cut fastener or slug in said throat, work puncturing and feeding mechanism including a 10 work feeding awl, means for moving said awl and said throat into and out of the line of drive, and means for adjusting said mechanisms, constructed and arranged to selectively adapt the machine for fastening 15 and for slugging operations.
15. In a machine for selectively inserting fasteners or slugs, the combination with driving means, of fastener controlling mechanism including means for guiding fastener stock 20 and slug stock, means for selectively receiving and placing the fastener stock or the slug stock in position to be driven by said driving means, work puncturing and feeding mechanism coöperating with said other 25 elements, adapted to puncture and feed the work and place the puncture in the line of drive, whereby selectively a fastener or a slug is placed to be driven by said driving means into said puncture, and means for adjusting 30 said mechanisms, constructed and arranged to selectively adapt the machine for fastening and for slugging operations.
16. In a machine for selectively inserting fasteners or slugs, the combination with 35 driving means, of fastener controlling mechanism including means for guiding fastener stock and slug stock, means for selectively receiving the fastener stock or the slug stock, means for selectively feeding and for 40 selectively cutting the fastener stock or the slug stock, adapted to selectively place in said receiving means a fastener or slug, work feeding and puncturing means coöoperating with said other elements, adapted to place 45 the puncture in the line of drive, whereby selectively a fastener or a slug is placed to be driven by said driving means into the formed puncture, and means for adjusting said mechanisms, constructed and arranged 50 to selectively adapt the machine for fastening and for slugging operations.
17. In a machine for selectively inserting fasteners or slugs, the combination with driving means, of means for guiding fastener stock and slug stock, means for selectively receiving the fastener stock or the slug stock, means for selectively feeding and for selectively cutting the fastener stock or the slug stock, adapted to selectively place in said receiving means a cut fastener or slug, work feeding and puncturing means coöoperating with said other elements, adapted to place the puncture in the line of drive, whereby selectively a fastener or a slug is placed to be driven by said driving 60 means into the formed puncture, and means for selectively adjusting said work puncturing and feeding means, constructed and arranged to selectively adapt the machine for fastening and for slugging operations.
18. In a machine for selectively inserting fasteners or slugs, the combination with driving means, of means for guiding fastener stock and slug stock, means for selectively receiving the fastener stock or the slug stock, means for selectively cutting the fastener stock or the slug stock, adapted to selectively place in said receiving means a fastener or slug, work feeding and puncturing means coöperating with said other elements, adapted to place the puncture in the line of drive, whereby selectively a fastener or a slug is placed to be driven by said driving means into the formed puncture, means for adjusting said guiding means, and means for adjusting said work feeding and puncturing means in accordance with said guiding means, constructed and arranged to selectively adapt the machine for fastening and for slugging operations.
19. A machine for selectively inserting fasteners or slugs, having driving means, means for guiding fastener stock or slug stock, means for selectively feeding and cutting fastener stock or slug stock, means for selectively receiving and placing the fastener stock or slug stock in the line of drive, and work puncturing and feeding mechanism including a work feeding awl movable 100 into and out of the line of drive, characterized by means for selectively adjusting said fastener and slug stock controlling means and said work feeding and puncturing mechanism, constructed and arranged to selectively adapt the machine for fastening and for slugging operations.
20. A machine for selectively inserting fasteners or slugs, having driving means, means for guiding fastener stock or slug stock, means for selectively feeding and for selectively cutting fastener stock or slug stock, means for selectively receiving and placing a fastener stock or slug stock in the line of drive, and work puncturing and feeding mechanism including a work feeding awl movable into and out of the line of drive, characterized by means for moving said awl to clear the work and to feed the work, and means for selectively adjusting said fastener and slug stock controlling means and the feeding movement of said awl, constructed and arranged to selectively adapt the machine for fastening and for slugging operations.
21. A machine for selectively inserting fasteners or slugs, having driving means, means for guiding fastener stock or slug stock, means for selectively feeding and for selectively cutting fastener stock or slug stock, means for selectively feeding and for selectively cutting fastener stock or slug 130

stock, means for selectively receiving and placing the fastener stock or slug stock in the line of drive, and work puncturing and feeding mechanism including a work feeding awl movable into and out of the line of drive, characterized by means for moving said awl to clear the work and to feed the work, and means for increasing the feeding movement of said awl without increase of 10 its clearing movement, constructed and arranged to adapt the machine for fastening and for slugging operations.

22. A machine for selectively inserting fasteners or slugs, having driving means, 15 for guiding fastener stock or slug stock, means for selectively feeding and for selectively cutting fastener stock or slug stock, means for selectively receiving and placing the fastener stock or slug stock in the line 20 of drive, and work puncturing and feeding mechanism including a work feeding awl movable into and out of the line of drive, characterized by means for moving said awl to clear the work and to feed the work, and 25 means for increasing the feeding movement of said awl adapted to decrease its clearing movement, constructed and arranged to selectively adapt the machine for fastening and for slugging operations.

30 23. A machine for selectively inserting fasteners or slugs, having driving means, means for guiding fastener stock or slug stock, means for selectively feeding and for selectively cutting fastener stock or slug stock, means for selectively receiving and placing the fastener stock or slug stock in the line of drive, and work puncturing and feeding mechanism including a work feeding awl movable into and out of the line of 35 drive, characterized by means for moving said awl to clear the work and to feed the work, and means for varying the feeding movement of said awl adapted to eliminate its clearing movement with maximum feeding movement of said awl, constructed and 40 arranged to selectively adapt the machine for fastening and for slugging operations.

24. A machine for selectively inserting fasteners or slugs, having driving means, 50 means for guiding fastener stock or slug stock, means for selectively feeding and for selectively cutting fastener stock or slug stock, means for selectively receiving and placing the fastener stock or slug stock in the line of drive, and work puncturing and feeding mechanism including a work feeding awl movable into and out of the line of 55 drive, characterized by means for selectively adjusting said work feeding and puncturing mechanism, constructed and arranged to move said awl in a single step during the 60 insertion of fasteners and in successive steps during the insertion of slugs.

25. In a machine for selectively inserting 65 fasteners or slugs, the combination with

driving means, of means for guiding strings of connected fasteners and connected slugs, means for receiving fasteners and slugs to be driven by said driving means, means for feeding and for cutting a selected string, 70 and means for adjusting said guiding means with respect to said receiving means, all constructed and arranged to selectively position in said receiving means a fastener or a slug. 75

26. In a machine for selectively inserting fasteners or slugs, the combination with driving means, of means for guiding strings of connected fasteners of different lengths and a string of connected slugs, means for 80 receiving fasteners and slugs to be driven by said driving means, means for feeding and for cutting a selected string, and means for adjusting said guiding means with respect to said receiving means, all constructed 85 and arranged to selectively position in said receiving means a fastener or a slug.

27. In a machine for selectively inserting fasteners or slugs, the combination with a driver, of a guide for strings of connected 90 fasteners and connected slugs, a throat adapted to receive a selected string, means for feeding and for cutting a selected string, and means for adjusting said guide with respect to said throat, all constructed and arranged to selectively position in said throat a fastener 95 or a slug.

28. In a machine for selectively inserting fasteners or slugs, the combination with a driver, of a guide for strings of connected 100 fasteners of different lengths and a string of connected slugs, a throat adapted to receive a selected string, means for feeding and for cutting a selected string, and means for adjusting said guide with respect to said 105 throat, all constructed and arranged to selectively position in said throat a fastener or a slug.

29. In a machine for selectively inserting fasteners or slugs, the combination with 110 driving means, of means for guiding strings of connected fasteners and connected slugs, means for receiving fasteners and slugs, to be driven by said driving means, means for feeding and for cutting a selected string, a work feeding awl, means for moving said 115 awl and said receiving means into and out of the line of drive, and means for adjusting said guiding means with respect to said receiving means, all constructed and arranged 120 to selectively position in said receiving means a fastener or slug.

30. In a machine for selectively inserting fasteners or slugs, the combination with a driver, of a guide for strings of connected 125 fasteners and connected slugs, a throat adapted to receive a selected string, means for feeding and for cutting a selected string, a work feeding awl, means for moving said awl and said throat into and out of the line 130

of drive, and means for adjusting said guide with respect to said throat, all constructed and arranged to selectively position in said throat a fastener or a slug.

5 31. In a machine for selectively inserting fasteners or slugs, the combination with driving means, of means for guiding strings of connected fasteners and connected slugs, means for receiving fasteners and slugs in 10 the plane of drive, means for feeding and for cutting a selected string when positioned in the plane of drive, and means for selectively positioning a selected string in the plane of drive, constructed and arranged to 15 position in said receiving means a selected cut fastener or slug to be driven by said driving means.

32. In a machine for selectively inserting fasteners or slugs, the combination with 20 driving means, of means for guiding strings of connected fasteners of different lengths and a string of connected slugs, means for receiving fasteners and slugs in the plane of drive, means for feeding and for cutting a 25 selected string when positioned in the plane of drive, and means for selectively positioning a selected string in the plane of drive, constructed and arranged to position in said receiving means a selected cut fastener or 30 slug to be driven by said driving means.

33. In a machine for selectively inserting fasteners or slugs, the combination with a driver, of a guide for strings of connected fasteners and connected slugs, a throat ar- 35 ranged in the line of drive and adapted to receive a selected string from said guide, means for feeding and for cutting a selected string when positioned to be received by said throat, and means for shifting said guide to 40 selectively position a selected string into co- operative relation with respect to said throat, all constructed and arranged to position in said throat a selected cut fastener or slug to be driven by said driver.

45 34. In a machine for selectively inserting fasteners or slugs, the combination with a driver, of a guide for strings of connected

fasteners of different lengths and a string of connected slugs, a throat arranged in the line of drive and adapted to receive a se- 50 lected string from said guide, means for feeding and for cutting a selected string when positioned to be received by said throat, and means for shifting said guide to selectively position a selected string into co- 55 operative relation with respect to said throat, all constructed and arranged to position in said throat a selected cut fastener or slug to be driven by said driver.

35. In a machine for selectively inserting fasteners or slugs, the combination with driving means, of means for guiding strings of connected fasteners and connected slugs, means for receiving fasteners and slugs in 60 the plane of drive, means for feeding and 65 for cutting a selected string when positioned in the plane of drive, a work feeding awl, means for moving said awl and said receiving means into and out of the line of drive, and means for selectively positioning a se- 70 lected string in the plane of drive, constructed and arranged to position in said receiving means a selected cut fastener or slug to be driven by said driving means.

36. In a machine for selectively inserting fasteners or slugs, the combination with a driver, of a guide for strings of connected fasteners and connected slugs, a throat ar- 75 ranged in the line of drive and adapted to receive a selected string from said guide, 80 means for feeding and for cutting a selected string when positioned to be received by said throat, a work feeding awl, means for moving said awl and said throat into and out of the line of drive, 85 and means for shifting said guide to se- lectively position a selected string into co- operative relation with respect to said throat, all constructed and arranged to position in 90 said throat a selected cut fastener or slug to be driven by said driver.

In testimony whereof I affix my signature this 6th day of October, 1917.

STEPHEN A. DOBYNE.
